UNITED STATES PATENT OFFICE

PETER LOMBARDO, OF BROOKLYN, NEW YORK

CARVING MACHINE FOR SMOKING PIPES

Application filed July 13, 1928. Serial No. 292,366.

This invention relates to carving machines particularly adapted for use in carving smoking pipes, the object of the invention being to provide a simple, efficient, inexpensive and easily operated machine for rapidly carving the bowls and stems of smoking pipes thereby to give them a rough or rustic appearance, now commonly desired.

In the drawings accompanying and forming part of this specification, Fig. 1 is a perspective view of the machine;

Fig. 2 is an end sectional view;

Fig. 3 is a detail view of a pair of carving tools, and Fig. 4 is a view of a pipe bowl and stem carved on this machine.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The machine in its preferred form thereof comprises a base or bed-plate 2 having a suitable opening 3 therein for attachment to the work bench when desired. Supported by this bed-plate is a series of rotary converging spindles 4 which carry at their ends suitable carving tools 5 each shown in the form of a U-shaped tool. For supporting these rotary spindles, the bed-plate is provided at opposite ends with two sets of upright posts 6 and 7, the posts 6 at the rear or driving end of the bed being spaced a greater distance apart than the posts at the working ends of the spindles.

In the form shown the posts 6 consisting of three posts, are clamped by suitable nuts 8 to the bed plate and for this purpose the plate is provided with a pair of elongated slots 9 through which the reduced ends 10 of the two outer posts extend whereby the posts may not only be clamped to the bed plate, but may be adjusted toward and from

the bed-plate, no adjustment thereof being necessary in view of the fact that the outer posts can be adjusted toward and from the center post. At the working end of the machine each of the set of three posts 7 is provided with reduced ends 11 extending through the bed-plate and secured in position by clamping bolts 12 projecting into the end of the plate. By means of these clamping bolts each of the posts 7 can be raised or lowered whereby one or more of the spindles may be raised or lowered so that all of the spindles will be in the same horizontal plane. Thus, it will be understood that by adjusting one set of posts, the spindles may be raised and lowered and by adjusting the outer posts of the other set the spindles may be adjusted laterally toward and from the intermediate spindle. As this last set of posts is spaced further apart than the other set, the rotary spindles converge toward the working ends thereof.

By means of the lateral adjustment the carving ends of the spindles can be adjusted to vary the size or relative position of the carvings of the pipe for either finer or larger carving, as desired. That is to say, the lateral adjustment enables the cutters to be brought closer together or spaced farther apart, according to the work that is to be done. When they are closer together, the carving devices do smoother or better work. The vertical adjustment is to insure that the carving devices will be in the same horizontal plane so that they will all do precisely the same work, for one carving device below the other will not do the proper work. The vertical adjustment, however, is very slight and the construction is sufficient to permit this slight adjustment.

As before stated, the carving spindles converge. If these cutters were spaced apart equally, the only result would be the making of three holes in the pipe bowl; whereas, by converging them, instead of making holes, they operate to give the rustic effect on the pipe. By providing the cutters with two prongs, six cutting edges are thus obtained, and by the formation of the two prongs, the result is the cutting of the wood and not the

boring thereof; whereas, if they only had one prong, the result would simply be the making of a hole, which would not look like carving. The cutters are run in opposite directions so as to maintain the pipe bowl steady in the hands of the operator, for if they were all run in one direction, the pipe bowl would be thrown out of the hands of the operator during the operation of the cutters.

10 Each of the spindles is provided with a grooved pulley 13, and a suitable belt 14, motor or otherwise driven, extends under the outer pulleys and over the intermediate pulley whereby the outer spindles are rotated right hand and the intermediate pulley left hand with a corresponding movement of the tools.

15 Each of the posts is provided at the top thereof with an opening 15 for the passage 20 of oil to suitably lubricate the spindles.

25 In the operation of the machine the operator holds the pipe bowl or stem, as the case may be, in position against the working ends of the spindles whereupon the pipe is carved by the rotary spindles in the manner described to give a rustic or rough finish.

30 It is to be understood that by describing in detail herein any particular form, structure or arrangement, it is not intended to 35 limit the invention beyond the terms of the several claims or the requirements of the prior art.

35 Having thus explained the nature of my said invention and described a way of constructing and using the same, although without attempting to set forth all of the forms in which it may be made, or all of the modes of its use, I claim:

40 1. In a machine for carving smoking pipes, the combination of a supporting bed, a series 45 of horizontally-located, converging, rotary spindles carried thereby and provided with carving cutters for simultaneously rusticly 50 carving smoking pipes to give them a rustic appearance, and means for rotating some of the spindles in one direction and the remainder thereof in the opposite direction.

55 2. In a machine for carving smoking pipes, the combination of a supporting bed, a series 60 of horizontally-located, converging rotary spindles carried thereby and provided with carving cutters for simultaneously rusticly 65 carving smoking pipes to give them a rustic appearance, and means for rotating some of the spindles in one direction and the remainder thereof in the opposite direction, each of said spindles having a cutter provided with a plurality of prongs.

70 3. In a machine for carving smoking pipes, the combination of a supporting bed, a series 75 of horizontally-located, converging, rotary spindles carried thereby and provided with carving cutters for simultaneously rusticly 80 carving smoking pipes to give them a rustic appearance, and means for rotating some of

the spindles in one direction and the remainder thereof in the opposite direction, each of said spindles having a U-shaped cutter.

85 4. In a machine for carving smoking pipes, the combination of a supporting bed, a series 90 of horizontally-located, converging, rotary spindles carried thereby and provided with carving cutters for simultaneously rusticly 95 carving smoking pipes to give them a rustic appearance, means for rotating some of the spindles in one direction and the remainder thereof in the opposite direction, and means for adjusting some of the spindles laterally.

100 Signed at 1822-3-4 Park Row Building, New York, N. Y., this 12th day of July, 1928. 105
PETER LOMBARDO.
